COMBINED MERCHANDISING CONTAINER AND TOY

William A. Ringler, Wayne, Pa.

Application July 6, 1935, Serial No. 30,070

9 Claims. (Cl. 46—11)

This invention relates to a combined merchandising container and toy and more particularly to a merchandising container which can be transformed into a toy boat when the contents have been removed.

The combined merchandising container and toy forming the subject matter of this invention is preferably made from waterproofed paper-board, although other materials which are resist-

5
appearance. The container is especially adapted for the packaging of food products relished by children, such as crackers, cookies, candies, nuts and cereals, but is equally adapted for the packaging of merchandise used by grownups. The container can be inexpensively manufactured by automatic machinery and can be sold at low cost. The container is strong and sturdy and can be made to carry merchandise which is

shown in the process of being transformed into the hull of a boat;

Fig. 8 is a perspective view of the boat and sail as completely assembled from the blanks shown in Figs. 1 and 2;

Fig. 9 is a fragmentary longitudinal cross sectional view through the boat structure shown in Fig. 8, this view being taken on line 9—9 of Fig. 8;

Fig. 10 shows a blank from which a combined container and toy boat of somewhat modified construction may be formed;

Fig. 11 shows a blank which has been cut and scored to provide a sail of somewhat modified shape;

Fig. 12 is a perspective view of a container as it appears when completely assembled from the blank shown in Fig. 10, one end wall of the container being partially opened to more clearly illustrate the construction;

Fig. 13 is a perspective view of the container shown in Fig. 12 transformed into the hull of a boat, certain parts being broken away to more clearly illustrate the construction;

Fig. 14 is a fragmentary longitudinal cross sectional view through the boat structure shown in Fig. 13, this view being taken on line 14—14 of Fig. 13;

Fig. 15 is a perspective view of a sailboat as it appears when completely assembled from the blanks shown in Figs. 10 and 11;

Fig. 16 shows a blank which has been cut and scored to provide a combined container and toy boat of further modified construction;

Fig. 17 is a perspective view of a container in the process of assembly from the blank shown in Fig. 16;

Fig. 18 is a fragmentary perspective view of the container shown in Fig. 17 with the top wall about to be closed to seal the contents within;

Fig. 19 is a perspective view of the completely assembled container as it appears when packed with merchandise;

Fig. 20 is a perspective view of the container shown in Fig. 19 in the process of being transformed into a boat hull;

Fig. 21 is a fragmentary perspective view looking into the interior of the fully assembled boat hull shown in Fig. 20;

Fig. 22 is a perspective view of the assembled boat hull shown in Fig. 20 with a sail applied;

Fig. 23 shows a blank from which may be formed a toy boat which may or may not be used as a container for merchandise;

Fig. 24 is a fragmentary perspective view of a toy boat in the process of assembly from the blank shown in Fig. 23;

Fig. 25 is a fragmentary perspective view of the boat shown in Fig. 24 at a more advanced stage of assembly; and

Fig. 26 is a fragmentary perspective view of the completely assembled boat formed from the blank shown in Fig. 23.

Similar reference characters refer to similar parts throughout the several views of the drawings and specification.

This invention is directed to the provision of a toy boat which can preferably be transformed from a practical container within which merchandise of various sorts may be economically packaged, shipped and stored. The toy boat may be made in various shapes and variously decorated to resemble rowboats, canoes, sailboats, battleships, submarines and freight and passenger vessels of various kinds. For purpose of illustration only there is shown in Figs. 1 to 8, inclusive,

one type of sailboat which can be transformed from a merchandising container preferably formed from waterproofed paperboard material. The boat hull and container here illustrated is formed from the blank shown in Fig. 1 which may be suitably cut and scored on a large production basis by an automatic cutting and scoring machine from large sheets or rolls of material.

The blank is so cut and scored as to provide a bottom wall 1 having side walls 2 and end walls 3 hinged thereto along the score lines a. The side walls 2 and end walls 3 are preferably joined together by bellows folds comprising triangular portions 5 and 6 all hinged together along the score lines a. The parts are so arranged that when the end walls 3 are raised upwardly into container form they will be inclined outwardly away from the bottom wall 1, and the bellows folds will be folded inwardly to lie against the inside face of the end walls 3.

The container shown in Figs. 4, 5 and 6 assembled from the blank shown in Fig. 1 is provided with side wall flaps 7 hinged to the side walls 2 along the score lines a. The side walls 2 may be provided with raised end portions 4 and the side flaps 7 separated from the end portions 4 by the cut lines c. Extending from the side flaps 7 are the extension flaps 10 and 11 respectively, hinging along the score lines a. When the blank is in set-up condition to provide a container, the side flaps 7 and the flap extensions 10 and 11 extend inwardly, as shown in Figs. 4 and 5, providing a closure for the container.

The raised end portion 4 may be provided with interlocking tabs 8 and 9 which extend inwardly, each tab being provided with an interlocking hook portion 14. Each of the end walls 3 may also be provided with an end flap 12 hinged thereto along the score lines a. The end flaps 12 are folded inwardly either under the interlocking tabs 8 and 9 as shown in Fig. 5, or over the interlocking tabs as shown in Fig. 8. The end flaps 12 provide a raised platform or deck which enhances the appearance of the boat structure. The end flaps 12 may also be provided with extension flaps 13 hinged thereto along the score lines a which are foldable inwardly, as shown in Fig. 6, when the container is closed, thus completely sealing the container. Merchandise of various kinds can be packed within the container, shown in Figs. 5 and 6, the merchandise being fully protected and enclosed.

When the container is to be converted into a toy boat, the side wall flaps 7 are folded inwardly to rest against the inside face of the side walls 2, as shown more particularly in Fig. 7. The extension flaps 10 and 11 will then seat against the inside face of the bottom wall 1, and may be held in this position by providing a cut-out notch 15 in the flap 10, into which the free edge of the flap 11 extends. The end flap extension 13 can then be folded into horizontal position, and held in this position by the locking friction which the bellows folds exert against the free edge of the tab extensions, as shown in Fig. 9. When assembled, the boat hull appears as shown in Fig. 8.

If a sailboat is desired, a blank 20 such as shown in Fig. 2, cut into the shape of a sail, is provided. Parallel extending score lines a extend transversely across the blank, so that the different sections of the sail may be bent at various angles to catch the breeze, as shown in Fig. 8. The score lines a also permit collapsed folding of the sail into the form shown in Fig. 3, so that it can be placed within the container, as shown

in Fig. 6. The sail is preferably provided with tabs 21 which are so arranged that they can be inserted through the cuts C provided in the side flaps 1, thus supporting the sail in erect assembled position within the boat hull. It will be noted that when thus assembled, the sail also assists in maintaining the flap extensions 10 and 11 in their proper position. An attractive sail-boat such as shown in Fig. 8 is thus formed.

10 The boat hull will float gracefully upon the water surface, and if made of waterproofed paperboard will not become water-logged, due to the fact that the hull is made from a single blank of unpunctured paperboard. The boat structure may

15 be decorated to resemble various types of boats, and can be given various shapes, as desired.

There is shown in Fig. 10 a blank of paper-board material which has been cut and scored to provide a container which has a larger containing capacity than the container formed from the blank shown in Fig. 1. In the form here shown, side wall extensions 27 and 28 are hinged to the side flaps 1 along the score lines a, which are substantially continuous with the top edge of the 20 raised side wall portions 4. Stated in other words, the side flaps 1 are substantially equal in height to the side walls 2. Severable lines of perforations b define the side flaps 1 from the raised end portions 4. End portions 25 and 26, 25 hinged to the raised side wall portions 4 along the score lines a, are separable from the flap extensions 27 and 28, along the lines of perforation b.

The blank shown in Fig. 10 is assembled to 30 form the container shown in Fig. 12, by raising the side walls 2 and end walls 3, and folding the bellows folds against the inside face of the end walls. The end flaps 12 and associated end flap extensions 13 are then folded inwardly, and 35 finally the side flap extensions 27 and 28 are folded inwardly in overlapping relationship. The flaps 27 and 28 may be glued or otherwise secured together, providing a completely closed container having a substantially uniformly rectangular body-section with inclined or bevelled 40 end walls. The flaps 27 and 28 may be made of the same width or of different widths, as desired. The container may be opened by withdrawing one 45 of the end flaps 12 permitting withdrawal of the contents through one end of the container, as shown in Fig. 12. This container has considerably more containing capacity than the container assembled in the form shown in Fig. 5.

In converting the container shown in Fig. 12 into a boat structure, the child tears through the 50 perforations b. The child then folds the top sections 7 of the side walls inwardly against the inside face of the bottom side wall sections 2. The side flap extensions 27 and 28 are then expanded into flat form so as to seat against the 55 inside face of the bottom wall 1, forming a complete boat hull of the form shown in Fig. 15. The end flap extensions 13 are then rebent to lie against the inside face of the end wall flaps 12, 60 and locked in this position by means of frictional contact with the bellows folds, as shown in Fig. 14.

The sail can be made of any desired shape or form. For purposes of illustration only, there is shown a sail 30 of somewhat modified shape, assembled with the boat hull shown in Fig. 15. 65 The sail may be made from a single blank of paperboard material, as shown in Fig. 11, provided with the transverse score lines a, to permit collapsed folding of the sail, and to permit flexing of the sail sections along the score lines to

more readily catch the breeze. The sail is secured in operative position by tearing through the line of perforations b in the side flaps 7, and then inserting the securing tabs 21 through the slit thus made. The container herein shown is 5 very economical to manufacture, and has substantially the merchandise-containing capacity of other cartons formed from paperboard material of equal area.

A container of somewhat modified form is 10 shown in Figs. 17 to 22 inclusive, formed from the blank shown in Fig. 16. In this form, the flap extension 28 is preferably made substantially equal in width to the width of the assembled container, and is provided with tuck-in flaps 37 15 hinged to the end portions 36 thereof, along the score lines a. The end flaps 12 are also provided with end extensions 38 having locking ears 39 which can be folded inwardly and inserted between the bellows folds and the end walls 3 of 20 the container, as shown in Fig. 17. The end walls can thus be held in set-up position without further securing means.

When the side and end walls have been connected together as above-described, the merchandise 25 is then packed therein, and the side wall extensions 10 and 28 are then folded inwardly, and the tuck-in flaps 37 inserted into the container, as shown in Fig. 19. A tubular sleeve 50, which may be formed of paperboard material, is 30 then telescoped over the container, and the flap extension 28 which forms a closure for the container is securely held in place. The container may be opened by slipping off the tubular sleeve 50 and swinging open the flap extension 28. 35

When the container is to be converted into a boat hull, the merchandise is first removed and the lines of perforations b are severed so as to separate the flap extensions 10 and 28 from the respective end portions 35 and 36, and also to separate the side flaps 1 from the raised end portions 4 of the side walls. The side flaps 1 are then folded inwardly so as to lie against the inside face of the side walls 2, and the side flap extensions 10 and 28 are positioned to lie flat 40 against the inside face of the bottom wall. The side flap extension 28 is preferably of sufficient width to frictionally grip the turned-in side flap 1, thus retaining the parts in assembled form. The end portions 36 and the tuck-in flaps 37 will 45 lie against the inside face of the end walls, as shown in Fig. 21. It will be noted that this transformable container may be held in assembled form by simple interlocking flaps without the use of glue, or other securing means. A sail 40 50 of any desired form may be positioned within the boat hull and held in place by the tabs 21 inserted through the slits provided by tearing out the line of perforations c in the side flaps 7.

In certain instances, it may be desirable to provide a package shaped into the form of a boat hull, the goods being packed directly in the hull, and the whole wrapped in "Cellophane" or other wrapping. There is shown in Figs. 24 to 26, inclusive, a container structure which is shaped to 60 resemble a boat hull, assembled from the blank shown in Fig. 23. In this form, the end flaps 45 fold inwardly against the inside face of the end walls 3, and are each provided with a foot portion 46 which rest against the inside face of the 65 bottom wall of the container. Cut lines c separate the side wall flaps 7 from the side walls 2, permitting the side flaps 7 to fold inwardly against the inside face of the side walls. The side flap extension 28, which is slightly wider than 70 75

the inside width of the assembled container, is preferably positioned over the flap extension 10 and the foot portions 46 so as to provide a smooth and even bottom surface for the container. The oversize side flap extension 28 grips the sides of the container, and holds the same in rigid assembled form without further securing means.

It is now seen that a container has been provided which is adapted for the packaging of a large variety of different kinds of merchandise, and when the contents have been removed can be used as or converted into a child's toy. The container may be economically manufactured, and, aside from its amusement qualities, provides an attractive and economical package for the packaging of merchandise.

While certain novel features of the invention have been disclosed and are pointed out in the annexed claims, it will be understood that various omissions, substitutions and changes may be made by those skilled in the art without departing from the spirit of the invention.

What is claimed is:

1. A toy boat formed from a single blank of waterproofed paperboard material including a bottom wall, side walls, inclined end walls, bellows folds connecting said side and end walls presenting a substantially leak-proof body, and an end flap extending inwardly from one of said end walls providing a raised deck at one end of the boat.
2. A toy boat formed from a single blank of waterproofed paperboard material including bottom, side, and end walls, bellows folds connecting said side and end walls presenting a substantially leakproof hull, said side walls having raised end portions, and end flaps extending inwardly from said end walls substantially the width of said end portions providing a raised deck at each end of the boat.
3. A toy boat formed from paperboard material including a bottom wall, side walls having raised end portions, end walls inclined outwardly with respect to said bottom wall and extending substantially to the top edge of said raised end portions, tabs extending inwardly from said raised end portions, and end flaps extending inwardly from said end walls providing a raised deck at each end of the boat.
4. A toy boat formed from a single blank of waterproofed material including a bottom wall, side walls having a reduced center portion and raised end portions, end walls inclined outwardly with respect to said bottom wall, bellows folds connecting said sides and end walls presenting a substantially leakproof hull, reinforcing side flaps extending from said side walls and positioned against the inside face thereof, and end flaps extending inwardly from said end walls providing a raised deck at each end of the hull.
5. A merchandising container transformable into a toy boat when the merchandise has been removed including, a bottom wall, side walls, end walls inclined outwardly with respect to said bottom wall, bellows folds connecting said side

and end walls providing a substantially leakproof construction, and a top wall hinged to one of said side walls providing a closure for said container, said top wall being collapsible to lie against the inside face of the bottom wall when the container is transformed into a boat.

6. A combined merchandise container and toy boat formed from a single blank of paperboard material comprising, a hull body adapted to contain merchandise, said hull body including a bottom wall, side walls, inclined end walls, bellows folds connecting said side and end walls presenting a substantially leakproof construction, and top wall flaps extending inwardly from said side walls providing a closure for the container, said top wall flaps being foldable inwardly to rest against the bottom wall when said container is transformed into a boat.

7. A merchandise container transformable into a toy boat including, a hull body comprising a bottom wall, side walls, inclined end walls, bellows folds connecting said side and end walls presenting a substantially leakproof construction, and top wall flaps hinged to said side walls providing a closure for the container, said side walls each comprising a top section and a bottom section, said top section being foldable inwardly and downwardly against the inside face of its corresponding bottom section when the merchandise has been removed thereby effecting transformation of said container into a boat.

8. A merchandising container transformable into a toy boat when the merchandise has been removed including, a hull body adapted to contain merchandise and comprising a bottom wall, side walls, end walls inclined outwardly with respect to said bottom wall, means connecting together said bottom, side and end walls, said side walls each comprising a top section and a bottom section, said top section being foldable inwardly and downwardly against the inside face of its corresponding bottom section when transformation of said container into a boat is to be effected, top flaps extending inwardly from said side walls providing a closure for the container, said top flaps being adapted to rest against the inside face of the bottom wall to provide an open boat structure when the contents have been removed from the container.

9. A merchandising container transformable into a toy boat including, a hull body comprising a bottom wall, side walls, inclined end walls, bellows folds connecting said side and end walls presenting a substantially leakproof construction, extensions hinged to said side walls, closure flaps hinged to said extensions, said extensions being foldable inwardly and downwardly against the inside face of its corresponding side wall when the merchandise has been removed thereby effecting transformation of said container into a boat, said top wall flaps then lying substantially flat against the inside face of said bottom wall.

WILLIAM A. RINGLER.
